VIBRATOR

Eugene Newnham, St. Louis, Mo., assignor to
 Knapp-Monarch Company, St. Louis, Mo., a
 corporation of Missouri

Application January 6, 1936, Serial No. 57,777

3 Claims. (Cl. 128—41)

The object of my invention is to provide a multi-speed vibrator which is simple, durable and comparatively inexpensive to manufacture.

A further object is to provide a vibrator of the type which can be held in the hand, and which has a vibration applicator with a means for controlling the degree of vibration, including a control member conveniently located on the vibrator so that it can be readily controlled as desired.

A further object is to provide a vibrator including an electro magnet and an armature responsive to energization thereof, the electro magnet having a plurality of windings and a switch being provided for varying the degree of energization by energizing either part or all of the windings.

A further object is to provide an electric vibrator including a stamping having a base portion to which a three-pole core is secured, and an armature portion terminating adjacent said poles, a winding being mounted on the center pole to provide an efficiently operating vibrator.

With these and other objects in view my invention consists in the construction, arrangement and combination of the various parts of the device, whereby the objects contemplated are attained, as hereinafter more fully set forth, pointed out in my claims, and illustrated in the accompanying drawing, in which:

Figure 1 is a perspective view of a multi-speed vibrator embodying my invention.

Figure 2 is a vertical sectional view on the line 2—2 of Figure 1.

Figure 3 is a vertical sectional view on the line 3—3 of Figure 2.

Figure 4 is a perspective view of a combined armature and core support used in my vibrator; and

Figure 5 is an electro-diagrammatical view showing the connections of current supply to the vibrator windings controlled by a variable switch.

On the accompanying drawing I have used the reference numeral 10 to indicate a supporting handle. The handle 10 has a ferrule 12 secured to an upper casing part 14. A complementary lower casing part 16 telescopes into the casing part 14, and the two are held assembled relative to each other by bolts 18.

The casing portion 16 is provided with an opening 20 through which an applicator shank 22 extends from the interior to the exterior of the casing. A vibration applicator 24 is mounted on the shank 22, preferably in a detachable man-

ner so that other applicators can be applied to the shank.

A dome-shaped cover 26 is provided on the casing member 14 and is held in contact therewith by a screw 28.

Within the casing formed by the parts 14 and 16 I provide a vibrator structure comprising a heavy sheet metal stamping A, best shown in Figure 4, a laminated core 30 and an electro-magnetic winding 32. The stamping A has an armature portion 34, a base portion 36 and a connecting portion 38. The base 36 is perforated as at 40 for the screws 18 to extend through, spacer sleeves 42 serving to retain the base 36 against the head of the casing portion 14 when the parts 15 are assembled.

The base 36 is provided with a pair of perforated ears 44, which receive screws 46, see Figures 2 and 3, extending into the core 30. The core 30 is of laminated character, the laminations being held assembled relative to each other by rivets 48.

The core 30 has a central leg 30a and a pair of end legs 30b, each of which terminates a slight distance from the armature 34. Whenever the winding 32 is energized with an alternating current, the magnetic impulses set up in the core by such energization intermittently attracts the armature, thus causing vibration of the applicator 24.

By forming the armature and the core in the shape illustrated, maximum attraction is secured, the magnetic lines of force issuing from the poles 30b entering the pole 30a, or vice versa, the armature being directly in the path of these lines. The connecting portion 38 being of metal is sufficiently resilient to permit vibration without the necessity of providing a hinge joint for the armature, and thus I am able to eliminate rattling and wear of such a joint, and provide a quietly operating vibrator.

It is quite often desirable to change the degree of vibration of a vibrator of the kind shown, and I am able to do this with the electrical hook-up shown in Figure 5. The winding 32 is provided with a center tap 32a, with which a wire 50 is connected, which extends to a contact 52. One end of the winding is connected directly with the current supply by a wire 54, and the other end is connected by a wire 56 with a contact 58. A switch 60 is connected with the other current supply wire 62. The switch 60 is a single pole, double throw switch.

When minimum vibration is desired, the switch 60 is moved to position engaging the contact 58,

whereby the entire winding 32 is energized. When maximum vibration is desired, it is moved to the other position, that is, engaging the contact 52, so that only a portion of the winding is energized. A portion of the winding offers less impedance to the flow of current, and accordingly a heavier current will flow, resulting in an ampere-turn increase and thereby a greater degree of vibration.

10 The switch 60 is suitably located with respect to the casing and handle of the vibrator, and in Figure 1 I have shown a control knob 64 therefor mounted on the casing adjacent the inner end of the handle. The knob 64 is accordingly in position for ready manipulation from the "off" to either the "high" or "low" position, as desired.

Although I have shown only a two position switch for high and low operation, it is obvious that other degrees of vibration can be obtained by taps in addition to the center tap 32a, and a three or four position switch can be used if desired. The tap 32a does not necessarily need to be centrally located, but can be at any position desired intermediate the ends of the winding 32, depending on the relative vibration desired in the "high" and "low" positions.

Changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

35 1. In an electric vibrator, a metal stamping having a pair of portions spaced from each other, one of said portions constituting an armature, a core having a center leg, a tapped current coil wound on said center leg, said core having a pair 40 of end legs spaced on opposite sides of said current coil, said armature extending across all three of said legs for attraction and vibration thereby upon energization of said current coil, a vibration applicator connected with said armature, and circuit connections with said tapped coil to selective- 45

ly energize different portions thereof to thereby secure different degrees of vibration of said armature relative to said coil.

2. In an electric vibrator, a metal stamping having a pair of portions spaced from each other, one of said portions constituting an armature, a core having a center leg, a tapped current coil wound on said center leg, said core having a pair of end legs spaced on opposite sides of said current coil, said armature extending across all three of said legs for attraction and vibration thereby upon energization of said current coil, a vibration applicator connected with said armature, circuit connections with said tapped coil to selectively energize desired portions thereof for securing different degrees of vibration of said vibration applicator, said stamping being provided with a pair of ears extending away from the plane of the portion of the stamping opposite said armature, said core having one end positioned adjacent said portion and against said ears and means for attaching said core to said ears and thereby mounting it relative to said stamping.

3. In an electric vibrator, a casing, a sheet metal stamping therein having a pair of portions spaced from each other, one of said portions constituting an armature and the other of said portions having diagonally offset perforations, a core having a center leg, a current coil wound on said center leg, said core having a pair of end legs spaced on opposite sides of said current coil, said armature extending across all three of said legs for attraction and vibration thereby upon energization of said current coil, a vibration applicator connected with said armature, said stamping being provided with a pair of ears extending away from the plane of said other portion, said core having one end positioned adjacent said other portion and against said pair of ears, means for attaching said core to said pair of ears and attaching means for extending through said perforations to said casing to thereby provide a rigid assembly of casing, stamping and core.

EUGENE NEWNHAM.
